UNITED STATES PATENT OFFICE.

JOHN K. HOTZE, OF ST. LOUIS, MISSOURI.

BRIDLE.

SPECIFICATION forming part of Letters Patent No. 357,008, dated February 1, 1887.

Application filed October 14, 1886. Serial No. 216,298. (No model.)

To all whom it may concern:

Be it known that I, JOHN K. HOTZE, of the city of St. Louis, in the State of Missouri, have invented a certain new and useful Improvement in Blind-Bridles, of which the following is a full, clear, and exact description, reference being had to the accompanying drawings, forming part of this specification, and in which—

10 Figure 1 is a side view of one of the cheek-pieces of leather by which the blinder is connected to the side strap. Fig. 2 is a perspective view of a side strap without a box-loop. Fig. 3 is a side view of a piece of leather from 15 which the box-loop is made. Fig. 4 is a side view of the outer layer of the cheek-piece to which the blinder is attached. Fig. 5 is a side view of the blinder. Fig. 6 is a side view of a modification in which the box-loop piece 20 and one of the cheek-pieces are cut in one piece. Fig. 7 is a side view of one side of the bridle in process of construction. Fig. 8 is a side view of one side of the bridle completed. Fig. 9 is a transverse section at 9 9, Fig. 7. 25 Fig. 10 is a transverse section at 10 10, Fig. 8. Figs. 11 and 12 are side views showing modifications. Fig. 13 shows the bridle upon a horse.

My improvements consist in a means for the 30 construction of the bridle with box-loops upon the sides in the manner described to enable the use of machine-work, or to make the process much easier when done by hand construction, and producing a superior article.

35 In all the better classes of bridles the side straps, A, have box-loops B. These have heretofore been sewed in place by hand-work by a tedious and expensive process, because no access of the hand can be had to the inner 40 side in making the last row of stitches, and for the same reason this last row could not be sewed by a machine.

In carrying out my improvement one edge, c, the inner cheek-piece, C, and one edge, b, of 45 the box-loop piece B are stitched in the side strap, A, by rows of stitches a a'. Then the box-loop piece B is folded over and its edge b' laid upon the cheek-piece C. Now the outer cheek-piece, C', is laid in position, with its

edge c' lapping over the edge b' of the box-loop piece. After this is done the row D of 50 stitches is made, connecting the two cheek-pieces together close to the side strap, and securing the edge b' of the box-loop piece between the cheek-pieces C and C'. 55

As a modification, the cheek-piece C' may be cut in one piece with the box-loop piece B. In this case the edge of the piece C and the edge of piece B C' are laid between the two parts of the side strap, A, and the two 60 seams a a' made. Then the piece B C' is folded over and the outer edges, c', of these pieces made to match and the row D of 65 stitches made, leaving the box-loop, as before described. In point of fact the seam D is generally a hidden seam upon the outside, the leather being scored and the stitches hidden by closing the lips of the score over the 70 stitches, according to well-known practice.

No novelty is claimed in the blinder E. 70

I claim as my invention—

1. A box-loop having one of its longitudinal edges turned inward under the loop-body and the other turned outward therefrom, substantially as set forth. 75

2. In a bridle, the combination, with a box-loop having one of its longitudinal edges turned inward under the loop-body and the other turned outward therefrom, of two cheek-pieces and a line of stitching for securing the 80 outturned edge between the cheek-pieces, an interposed strip between the inturned edge and the loop-body, and a line of stitching for securing the strip and inturned edge together, substantially as set forth. 85

3. In combination with strap A, a cheek-piece, C, a box-loop, B, having an inturned longitudinal edge, stitching which secures the inturned edge of loop B and cheek-piece C to strap A, another cheek-piece, C', an outturned longitudinal edge on box-loop B, and a line of stitching, by which the outturned edge is secured between the cheek-pieces C and C', substantially as set forth. 90

JOHN K. HOTZE.
